WRITING INSTRUMENT

Larry Raszl, Jericho, N.Y., assignor to Laka Tool and Stamping Company, Westbury, N.Y.

Application March 26, 1957, Serial No. 648,596

3 Claims. (Cl. 120—42.03)

The present invention relates to writing instruments and more particularly, to writing instruments wherein the writing element of the instrument is capable of being propelled into a writing position and retracted fully into the body of the instrument when not in use. Such instruments are generally referred to as retractable writing instruments.

It is an object of the present invention, as it is the desideratum of instruments of this kind, to provide a structural combination of elements that will facilitate its manufacture by modern mass production techniques. In this way, the instruments resulting from such mass production can be manufactured in wholesale quantities with the knowledge that each one of them and each of their parts is of uniform construction and detail. The consequent cost of manufacture and assembly is therefore materially reduced.

Keeping this in mind, the present invention is of necessity simple in structural details, requiring relatively few moving elements, yet providing the important cooperation of operative structures to result in an instrument that is unusually inexpensive and simple in operation.

In carrying out the objects of the invention, a feature resides in the provision of a plunger and plunger spring of unique configuration and details, overcoming the costly and cumbersome details of prior art structures. In the present invention, a single plunger spring of relatively small size having but a single leg that acts in cooperation with but a single area of the writing instrument serves to perform the necessary guiding and locking operations. This is in distinction to the larger and more expensive structures of such prior art devices as Liguori Patent No. 2,715,888, wherein the plunger spring must act on diametrically interior opposite walls or areas of the body of the writing instrument to provide the necessary stability of parts during the guiding and locking operations.

Other and further objects of my invention reside in the structures and arrangements hereinafter more fully described with reference to the accompanying drawings in which:

Fig. 1 is a longitudinal section through the assembled writing instrument constructed in accordance with the teaching of the invention.

Fig. 2 is an exploded view in perspective of the writing instrument.

Fig. 3 is a detail of the upper portion of the instrument with parts thereof broken away.

Fig. 4 is a transverse section taken along lines 4—4 of Fig. 3.

Fig. 5 is a transverse section taken along lines 5—5 of Fig. 1.

Fig. 6 is a perspective view of the plunger spring release button.

Referring now to the drawing wherein the writing instrument is generally identified by the numeral 10 for broad purposes of identification. Writing instrument 10 comprises an elongated two-part housing 12 and 14 that is secured together intermediate its ends by a threaded

2

plug 16. The front end of the housing 12, 14 is provided with an opening 18 to accommodate a writing element to be described, while the rear of the housing is provided with an opening 20, through which a plunger, to be described, is adapted to be longitudinally movable.

The plug 16, being cylindrically shaped is knurled at its upper end to be press-fitted into engagement with the interior surface of the front end of the upper or rear portion of the housing 14. The other end of plug 16 is threaded as at 22 for further engagement with the rear threaded end 23 of the front portion of the housing 12 as shown in Fig. 1. The plug 16 thus serves to secure together the front and rear portions 12 and 14 of the elongated housing. The plug 16 is provided with an axially extending central opening 24 through which a writing element 26 extends for longitudinal guided movement within the housing 12, 14.

The writing element 26 extends for a substantial portion of the length of the elongated housing 12, 14 and has its forward writing end 28 in axial alignment with the front opening 18 for projection thereto into a writing position. An enlargement or stop 30 is formed along the length of the writing element 26 intermediate its forward tip 28 and the plug 16. The enlargement provides a surface on which the rear end of a compressed spring 32 may bear. The other end of the compression spring 32 seats against the interior tapered walls of the front portion of the housing 12. In its compressed condition, the spring 32 normally and constantly applies a force against the stop 30 that urges the writing element 26 from its extended or writing position to its retracted position within the housing, as shown in Fig. 1.

In order to actuate or move the writing element 26 longitudinally within the housing from its retracted position as shown in Fig. 1 to a projected or advanced writing position (not shown), a rear end or longitudinal portion 34 of the writing element is securely seated within an axially extending centrally disposed opening 35 defined in a plunger 36.

Plunger 36 has a forward exterior cylindrical surface 37 of substantially the same dimension as the interior of the rear portion 14 of the housing, for guiding cooperation during the longitudinal movement of the plunger 36 in the rear of the housing 14. Plunger 36 includes a finger operated extension 38 at its extreme rear end that projects beyond and through the rear opening 20 of the housing 14. The extension 38 facilitates manual finger engagement in order to operate the writing element 26. Intermediate the extension 38 and the enlarged shoulder 37 is a body portion 40 having a shoulder 41 that is adapted to cooperate with the wall defining the rear opening 20. The shoulder serves to assure only limited longitudinal movement of the plunger 36 outwardly of the opening 20.

Defined in the plunger 36 is a radial recess 42 that extends longitudinally along the plunger body 40 intermediate the ends thereof. Referring to Fig. 1, it will be noted that the recess 42 has a portion 44 thereof which is deeper at its rear or one end than at the other portion 46.

Seated within the recess 42 is a plunger spring generally identified by the numeral 48 (see Fig. 2). The plunger spring 48 serves as a locking member to retain the writing element 26 in its extended or advanced writing position after the same has been actuated longitudinally in the housing by the plunger 36. Spring 48 is of relatively short length, composed of resilient material and including a pair of spaced radially biased legs 50 and 52. The legs 50 and 52 each being formed of a resilient material, are jointed at a loop or bend 54.

Leg 52, which may be termed the actuator leg, is formed with a substantially planar surface 56 that termi-

nates in a toe 58 bent at an angle relative thereto. The planar surface 56 is adapted to seat on and along the substantially planar surface of the shallower recessed portion 46 of the radial recess 42 while the toe 58 extends into the deeper recess 44 and into engagement with the lower corner thereof as seen in Fig. 1.

The upper leg or locking member 50 being resiliently biased away from its companion leg 52, is bent upwardly at 60 to define locking surfaces 62. The locking surfaces 62 result from the formation of a transversely extending shoulder that is narrowed at its central portion, and which portion extends upwardly still further at 64. Portion 64 then curves over about itself to form a substantially inverted U shape. The inverted U shape 64 thus defines a pair of guiding surfaces. One of said guiding surfaces being on the side adjacent to the locking shoulders 62 and the other being formed on the side of the bent-over portion 64 at 66.

The opposite sides of the two legs 67 and 66 of the inverted U shaped formation 64 serve as pairs of guiding surfaces that cooperate and engagingly co-act with a pair of spaced guide walls 68 and 70 defined as a longitudinal cut-out or opening in the upper portion 14 of the housing. The guide means defined in the housing portion 14 by the spaced walls 68 and 70 terminates in a transverse, locking means 72 that is adapted to receive and engagingly co-act with the radially operating transverse locking shoulders 62.

Mounted on the housing on the rear portion 14 thereof is a pocket clip 74 that overlays and covers the T shaped guide and lock means of the housing. The pocket clip is secured in this location by a set of transversely separated prongs 76 that are adapted to be inserted radially into corresponding holes 77 (Fig. 3), these to be bent inwardly toward each other in a manner more clearly seen in Fig. 5.

The location of the prongs 76 is of importance in the operation of the invention. Because the prongs extend into the housing when they are bent inwardly, they lower or depress the locking leg 50 slightly radially inward. The depression is of such extent that the locking shoulders 62 of the plunger spring 48 are positioned out of rubbing contact or engagement with the interior surface of the housing 14. This provision thereby completely eliminates the wear that might normally occur if the shoulders 62 were permitted to rub against the housing.

In operation, with the writing element 26 in its retracted position as shown in Fig. 1, the plunger 36 is depressed by finger pressure applied to it at end 38. The force applied to plunger 36 need only be of such magnitude as to overcome the normal force of the spring 32.

As the plunger 36 is depressed, a longitudinally directed force is applied to the toe 58 of the plunger spring 48. This force is transmitted obliquely along the toe in a direction normally tending to lift the planar surface 56 from its seat in the shallow part of recess 42. The result is a squeezing force on the bend 54 that is transmitted to the locking member 50. This squeezing force adds to the normally radially directed tendency of the leg 50 to space itself from the leg 52, resulting in an increased radial movement of the leg 50 toward its engagement with the guide means and lock means of the housing 14.

All throughout the longitudinal movement of the plunger 36 the guide surfaces on the edges of the legs of the inverted U 64, co-act and engage with the walls 68 and 70 to guide the locking shoulders 62 into engagement with the locking means 72. Because the U shaped bend 64 results in at least a plurality of guiding surfaces, each of which are spaced one from the other, while the legs 50 and 52 are retained in the recess 42 from transverse movement relative to the plunger 36, the plunger in turn is restricted from rotative movement relative to the housing 14.

Hence the longitudinally spaced guide legs 66 and 67

5

of the bend 64 provide a double bearing engagement between the guide means 68, 70 of the housing and the operative plunger 36. This engagement prevents the plunger from rotating within the housing and provides a guiding cooperation therebetween.

As the plunger 36 is depressed longitudinally within the housing to extend the writing end 28 through the opening 18 and into its writing position, the locking member 50 is also moved to position its locking shoulders 62 into coincidence with the locking means 72. During this continued longitudinal movement, the shoulders 62 are aligned with the transverse opening 72 and are radially biased into the confines thereof.

The prongs 76 do not interfere with this radial operation of locking member 50. Its arm between the bend 60 and shoulders 62 is sufficiently long to compensate for degree of the angle that leg 50 assumes by virtue of the prongs 76 when the shoulders 62 are aligned with opening 72.

20 When once engaged in the opening 72, the plunger spring 48 retains the writing element 26 in its writing position. This locking action of the spring 48 is enhanced by virtue of the force exerted by the return spring 32, now compressed. Spring 32, in exerting its 15 longitudinal force, places the shoulders 62 into engagement with the rear walls of the opening 72, creating an increasing engaging force thereat.

In order to release the locking action and cooperation between the plunger spring 48 and the lock means 72 30 of the housing, it is merely necessary to apply light manual pressure to a release button 78 mounted in the clip 74. The button 78 extends longitudinally in an accommodating opening provided in the clip 74 for radial manual finger depression. The underside 80 of the 35 button 78 is in constant engagement with the longitudinally movable bend 64 of the plunger spring. Hence when the plunger spring is moved to its locking position as previously described, the slight inward radial depression of the button 78 moves the locking shoulders 62 from engagement with the transverse opening 72, thereby 40 releasing the locking engagement therebetween.

The shoulder 82 (Fig. 6) of the release button prevents its displacement from the clip 74 to retain the release button in constant cooperating engagement with the bend 64.

45 After radial inward movement of the release button 78 against the bend 64 to release the locking engagement between the shoulders 62 and the locking means 72, the constant urging of the compressed spring 32 immediately retracts the writing element into the housing.

50 This retractive movement is transmitted from the writing element at its rear end portion 34 thereof to the plunger 36. The plunger is thus returned to its position as shown in Fig. 1 wherein its shoulder 41 seats against the wall defining the rear opening 20 of the housing. 55 Throughout the described movement and operation, plunger 36 is constantly properly and non-rotatably guided by the plurality of longitudinally spaced guiding surfaces formed along the edges of the legs of the inverted U shaped portion 64.

60 While there have been shown and described and pointed out the fundamental novel features of the invention as applied to a preferred embodiment thereof, it will be understood that various omissions and substitutions and changes in the form and details of the device illustrated and in its operation may be made by those skilled in the art, without departing from the spirit of the invention. It is the intention, therefore, to be limited only as indicated by the scope of the claims appended hereto.

I claim:

1. In a writing instrument, a housing having front and rear openings, an inverted substantially T-shaped slot adjacent to said rear opening, a writing element movable in said housing for projection at its front end

through said front opening into a writing position, means normally urging said writing element from its writing position, a plunger member in said housing adjacent to its rear opening, said plunger member having an enlarged shoulder portion guidingly cooperating with the interior of said housing and engaging said writing element for movement therewith, a finger extension extending from said plunger beyond the rear opening and adapted to be actuated to urge the instrument into writing position, and a body portion between said shoulder and finger members, said body portion having a shallow recess and a contiguous deep recess, a spring member seated in said shallow recess and extending into said deep recess, said spring member including a locking leg and a U-shaped portion, said U-shaped portion extending substantially transversely from said locking leg and extending through said T-shaped slot adjacent to the walls thereof to provide a pair of guiding surfaces when the plunger is actuated and to restrict said plunger from rotative movement relative to the housing, and means on said housing overlying said U-shaped portion and adapted to release the movable writing element into retracted position.

2. In a writing instrument, a housing having front and rear openings, an inverted substantially T-shaped slot adjacent to said rear opening, a writing element movable in said housing for projection at its front end through said front opening into a writing position, means normally urging said writing element from its writing position, a plunger member in said housing adjacent to its rear opening, said plunger member having an enlarged shoulder portion guidingly cooperating with the interior of said housing and engaging said writing element for movement therewith, a finger extension extending from said plunger beyond the rear opening and adapted to be actuated to urge the element into writing position, and a body portion between said shoulder and finger members, said body portion having a shallow recess and a contiguous deep recess, a spring member seated in said shallow recess and extending into said deep recess, said spring member including a locking leg and a U-shaped

portion, said U-shaped portion extending substantially transversely from said locking leg and extending through said T-shaped slot adjacent to the walls thereof to provide a pair of guiding surfaces when the plunger is actuated and to restrict said plunger from rotative movement relative to the housing, and means on said housing overlying said U-shaped portion and adapted to release the movable writing element into retracted position, said spring member including a substantially planar actuator leg connected to said locking leg in a resiliently biased relation, said planar leg seating on and along said shallow recess and a toe member extending from said planar leg and terminating in said deep recess, said locking leg having a transversely extending bent portion adapted to extend through the transverse portion of said T-slot when in latched position, and said U-shaped guide portion extending from said bent portion and adapted to extend through the vertical portion of said T-slot to guide the plunger member.

3. The combination of claim 2, wherein said release means comprises a pocket clip member and prong means extending from said pocket clip member into said housing and engaging said locking leg whereby said prong means depresses the locking leg slightly radially inward so that said bent portion of locking leg is positioned out of rubbing contact with the interior surface of the housing.
